Application October 28, 1942, Serial No. 463,699
In Great Britain December 12, 1941

13 Claims. (CL 315—40)

1

The present invention relates to arrangements for producing an electron beam particularly for electron discharge devices comprising high frequency resonant chambers.

In oscillators of the velocity modulation type for very short wavelengths it is in general desirable to use electron streams of very high current density. This follows at once from the fact that for a given beam voltage the mechanical dimensions of the circuit are reduced as the wavelength is reduced and consequently a smaller cross sectional area of beam must be used. This means that in order that an adequate power output should be obtained either voltage or current density must be increased.

An object of this invention is to provide arrangements for producing electron beams in which very large current densities may be obtained and are used to produce oscillations.

This is in general accomplished by employing a substantially uniform magnetic field having lines of magnetic force substantially parallel to an electron emitting surface, arranged to deflect electrons laterally into a path generally parallel to the surface in which the electrons are concentrated to produce the desired current densities. A further object of the invention is to utilize the electrons in said path to produce oscillations in a resonator, and particularly to obtain this result by velocity modulation.

A further object is to provide an arrangement of the indicated type having a central resonator or annular series of resonating cavities surrounded by an annular cathode.

The invention also includes an arrangement in which the oscillations are maintained by secondary emission of electrons produced by the impact of velocity modulated electrons on a cathode.

The invention will be further described with reference to the accompanying drawings in which Fig. 1 is a diagram to show the theory of the invention.

Fig. 2 is a diagram to show the effect of space charge upon arrangements according to the invention.

Fig. 3 is a graph to show variation of current density with distance from the cathode in arrangements according to the invention.

Figs. 4, 5, 6 and 7 are diagrammatic drawings showing constructions according to the invention.

Fig. 8 is an enlarged view of part of Fig. 7 showing two lines of force.

Figs. 9 and 10 show diagrammatically two

other forms of the invention using two resonant cavities and

Figs. 11 and 12 show in vertical and horizontal cross section respectively a practical form 5 of the construction shown in Fig. 9.

Referring to the drawings:

In Fig. 1, a plane emitting surface 1 is illustrated opposite and parallel to a plane anode 2 and a uniform magnetic field is applied perpendicular to the plane of the diagram.

Then, as is well known, the path of an electron emerging from the cathode 1 with zero velocity will be cycloidal as shown by the tracks 3, 4 of electrons emitted from the points 5, 6.

15 From an examination of Fig. 1 it will be observed that the current density in the direction of the arrow A at the point 7 is very large, compared to the emission density at the cathode surface, all the emission between the points 5 and 6 being concentrated between the two lines 8 and 9.

An application of this large current concentration may be made in the design of ultra high frequency oscillators and power amplifiers, particularly though not solely of the velocity-modulation types. It may be noted here that the effect of full space charge limitation has been considered and is found actually to be advantageous to the current concentration desired. 20 In Fig. 2 are shown electron paths which can be obtained in such conditions.

Arrangements according to the invention for producing electron current concentrations have a particular advantage in that the concentrated beam of electrons is produced only after the electrons have attained a considerable velocity. Space charge limitation of the cathode emission does not therefore make it necessary to use very high voltages or very close spacings of the electrodes as is the case in many known constructions for the production of concentrated beams. 35 It is clear from Fig. 2 that at the plane A—A¹ where the electron velocity is small and space charge effects might be serious, the current density is low while at B—B¹, the current density is much increased and the velocity of the electron is also large.

The variation of current density i with the distance x from the cathode is shown in Fig. 3 for space charge negligible (curve 1) and space charge limited (curve 2), w being the emission density.

50 Electron beam producing arrangements according to the invention, as already inferred, are particularly adaptable for incorporation in oscil-

lators for use at very short wavelengths, of the order of 3 cm. or less. In such oscillators resonant circuits of the types usually used at longer wavelengths become very small. In consequence of this, the amount of electron current which can be used also becomes small. In order to obtain high powers, therefore, it is important to use systems in which the useable cathode area is as great as possible when measured in terms of λ^2 , (λ is the wave length). Since circuit losses tend to become serious at such short wavelengths, it is also important that circuits should be designed to give the highest possible impedance at the point or points traversed by the driving electron stream, and that the current density in this stream should be as great as possible.

An embodiment of the invention about to be described satisfies all these requirements and is in many ways an appreciable advance on existing circuit designs for such high frequencies.

Figs. 4-8 show embodiments employing a single high frequency resonant chamber. The chamber in Fig. 4 has a single gap or aperture whilst in Figs. 5-8 the chamber has a plurality of apertures arranged around the circumference of the chamber.

Referring to Figs. 5-8 a cross section of an electron discharge device embodying the invention is shown, the dotted lines showing the tracks of a few typical electron paths. The structure consists of a large cylindrical cathode 1, coated on the inner side and containing within it a segmented anode consisting of a series of strips B of a cylinder coaxial with 1. A magnetic field is applied parallel to the axis of the cylinders. The tracks 11, 12, 13, Fig. 5 show the form of path traversed by a series of electrons leaving 1 in the absence of oscillation, and show how the whole of the emission from a considerable area of 1 will be concentrated into a current of very high density passing closely across the gap between two of the strips B as long as the potential difference between 1 and B is suitably matched to the magnetic field employed.

Now, oscillations may be set up in the gaps between the strips B of a type characterized by the electric force lines, the instantaneous distribution of which is shown at 14, Fig. 6. It will be noted that an even number of the strips B should be used. The wavelength will be very short; if n strips are used, it will be of the order

$$\frac{4\pi r}{n}$$

and will be independent of the length of the system perpendicular to the paper. r is the radius of the cylinder on which strips B lie. Energy will be abstracted from the electron stream as it crosses the gaps, the transfer of energy being a maximum when the electrons remain in the field of the gap for about 1.2 cycles of the oscillation. Now examination of the behavior of the electrons when oscillation takes place shows that the efficiency of operation will be at least double that of a diode using the same mechanism of excitation with an electron beam, i. e. of the order of 40%. This is due to the fact that only electrons which have lost kinetic energy, and thus contributed to the maintenance of the oscillation, will be collected by the strips B if the magnetic field is properly adjusted. Others will return to the cathode and will not, therefore, absorb any D. C. energy. Four typical electron tracks 15-18 are shown in Fig. 7 corresponding to electrons which have left the cathode at intervals of $1/4$ cycle. Two, namely

15 and 16, which are shown more clearly in the enlarged drawing Fig. 8, lose considerable amounts of their D. C. energy and are collected by the anode; one, namely 17 suffers little energy change and returns gently to the cathode, and the other 18 gains energy from the H. F. field and returns with it to the cathode.

The magnetic field will not in fact be so critical as might be suggested by the discussion above as an increase, although removing the electrons slightly from the strongest field, will only allow electrons which have lost a useful amount of energy to reach the anode.

If very high voltages are used, the extremely high emission available might make dissipation of the energy at the anode a serious difficulty on continuous wave operation, but the system will still be extremely suitable for use as a pulsed generator, and for a given desired power output, the large dimensions of the system compared with the wavelength will allow the dissipation to be spread over a large area.

The oscillating system may, of course take forms other than the cylindrical strips B. For instance, straight flat strips of, for example, tungsten sheet could equally well be used, the dimensions being appropriately adjusted, or any other sectional form giving suitable gaps when they can be reached by the electron stream with large high frequency fields imposed across them.

The strips may be mounted on radial supports from the centre of the cylinder formed by strips B or they may be supported in any suitable insulating material, and the frequency may be adjusted within reasonable limits either by any convenient distortion of the system so built up or by the movement of a conductor near the end of the system.

The power generated may be withdrawn in known manner by a probe near the end of the system in the manner shown in Fig. 12, or by any other well-known method, the output preferably being brought through the vacuum envelope by a suitable wave guide to avoid unnecessary losses.

The lengths of the strips perpendicular to the section shown in the figures are not important except insofar as it is desirable that they should not be such as to cause resonances at wavelengths which could readily be excited in the same range of voltage and magnetic field.

In Fig. 9 two high frequency resonant chambers 24, 25 are used as in a now well known klystron circuit and may be coupled externally if the arrangement is to be used as an oscillator. Figs. 11 and 12 show a constructional form of tube according to Fig. 9. The two cavities 24 and 25 are formed in a block 26 of copper, which is however, preferably formed of a series 26' of superposed plates in the manner described in co-pending application Serial No. 457,789.

This block 26 (or superposed plates 26') is placed within a copper cylinder 28 having top and bottom plates 29 of magnetic material. Above and below the block 26 are copper plates 27 to support the block 26 centrally of the height of the cylinder. Plates 30 of mica or similar insulating material support a copper plate 31 at a suitable distance from the cavities 24, 25. Supported on a portion of the copper plate 31 with the intervention of insulation 32 is a cathode 1. A coaxial line connector 32 is sealed through a glass bead 34 in turn sealed through the cylindrical wall 28 and the inner conductor 33 thereof just protrudes into the cavity 25. Lead in wires 35 for the cathode heater are sealed through

the wall 28 by means of a glass bead. The wall 28 and top and bottom plates 29 are welded together or otherwise joined in a vacuum tight manner and the whole vessel is evacuated. A horse shoe magnet 36 serves to support the vessel by magnetic attraction and to provide the necessary magnetic field within the vessel.

The operation of the device will be clear from the description given above. A suitable potential difference is applied between the outer cylinder 28 and the cathode 1. Electrons emitted by the cathode 1 are attracted towards the block 26 and their paths are bent by the magnetic field so that they follow paths shown in Fig. 9. The electron beam in passing the cavity 24 is velocity modulated and when passing the portion of the block 26 between cavity 24 and cavity 25 the electrons are bunched. When the bunched electrons pass the cavity 25 they give up energy to the high frequency field within the cavity. The resonant cavities 24 and 25 are closely coupled without the introduction of any special coupling devices and oscillations of nearly the same amplitude and of the same or opposite phase in the two cavities 24, 25 are maintained by the beam. There is a series of discrete beam velocities for which a maximum occurs in the high frequency energy transferred from the beam, giving a series of possible operating voltages. Fig. 10 shows the invention embodied in an arrangement using secondary electron emission amplification and serving as an oscillator or power amplifier.

It is not necessary in the embodiment shown in Fig. 10 that the modulating and output circuits, e.g. 19 and 20 should be at the same potential; it may be advantageous to have the output circuit 20 at a higher potential, the electrodes, of course, being so disposed as to give suitable electron paths.

The secondary electron emitting surface 21 is as shown so arranged as to receive the electrons returning towards the first emitting surface 1. On impact with the surface 21, the primary electrons falling thereon, cause secondary electrons to be emitted and the stream 23 of electrons from 21 is condensed in the same manner as already described. The primary electron stream 22 is modulated in intensity by the high frequency field across the aperture of resonant chamber 19. This modulated stream 22 produces an amplified modulated stream of electrons 23 which excites the resonant chamber 20 as they pass across the aperture therein in accordance with the modulation.

What is claimed is:

1. An electron discharge device comprising a cathode having a substantially cylindrical electron emitting surface, a tubular anode located concentrically within the cathode surface and having a plurality of openings each communicating with a cavity operating as a cavity resonator located within the anode, means for producing a potential difference between the cathode and anode, means for maintaining a magnetic field in the space between the anode and the cathode surface having lines of magnetic force parallel to the axis of the anode and an intensity at which electrons emitted at said cathode surface are deflected into arcuate paths passing adjacent to said openings; and means for extracting high frequency energy from at least one cavity resonator.

2. An electron discharge device with a means for producing a concentrated electron beam comprising a cavity resonator, a wall of said resona-

tor provided with an opening through which the oscillating field of the resonator can extend, a cathode having an electron emitting surface of substantial length in one direction opposite and equidistant from the resonator wall, means connected to said resonator and said cathode for producing a potential difference therebetween, and means adjacent said cathode and said resonator for maintaining a magnetic field therebetween, the field having lines of force perpendicular to said direction of the length thereof and an intensity adapted to deflect electrons emitted along the length of said surface in arcuate paths having a substantial portion equidistant from the resonator wall adjacent the opening and concentrated across the opening.

3. A device according to claim 2 in which the cathode surface is tubular, and the anode surface is symmetrically arranged around the axis of the cathode surface within the cathode.

4. A device according to claim 2 in which the arcuate electron path extends back to the cathode.

5. An electron discharge device with means for producing a concentrated electron beam comprising a cavity resonator, a wall of said resonator provided with an opening through which the oscillating field of the resonator can extend, a cathode adjacent to and facing the opening, an electron emitting surface of substantial length in one direction on said cathode equidistant from the resonator wall, means connected to said resonator and said cathode for producing a potential difference therebetween, and means adjacent said cathode and said resonator for maintaining a magnetic field therebetween, the field having lines of force parallel to said emitting surface and perpendicular to said direction of the length thereof and an intensity adapted to deflect electrons emitted along the length of the surface in arcuate paths having a substantial portion equidistant from the resonator wall adjacent the opening and concentrated across the opening in the resonator wall and terminating in the cathode.

6. An electron discharge device with means for producing a concentrated electron beam comprising an anode with a cavity resonator therein, a flat wall of said anode being provided with an opening through which the oscillating field of the resonator can extend, a flat cathode parallel to said wall with the opening, an electron emitting surface of substantial length in one direction on said cathode, means connected to said anode and cathode for producing a potential difference therebetween, and means adjacent said anode and cathode for maintaining a magnetic field therebetween, the field having lines of force parallel to said emitting surface and perpendicular to said direction of the length thereof and an intensity adapted to deflect electrons emitted along the length of said surface in arcuate paths having a portion substantially parallel to said anode wall and concentrated across the opening and terminating in said cathode.

7. An electron discharge device for sustaining ultra high frequency oscillations comprising two cavity resonators each having a wall with an opening through which the oscillating fields of the resonators can extend, a cathode having an electron emitting surface of substantial length in one direction, said cathode being opposite and equidistant from the resonator walls having said openings, means connected between said resonators and said cathode for producing a potential

difference therebetween, and means adjacent said device for maintaining a magnetic field between said resonators and said cathode, the field having lines of force parallel to said emitting surface and perpendicular to the length thereof and an intensity adapted to deflect electrons emitted along the length of said surface in arcuate paths having a portion substantially parallel to said resonator walls adjacent the openings in succession and concentrated across the openings.

8. An electron discharge device for sustaining ultra high frequency oscillations comprising a first and second cavity resonator each having a flat wall with an opening through which the oscillating fields of the resonators can extend, said walls being aligned and said openings being adjacent each other, a flat cathode parallel to said aligned resonator walls, an electron emitting surface of substantial length in a direction parallel to said openings and mounted on said cathode, means connected to said cathode and said resonators for producing a potential difference therebetween, means adjacent said device for maintaining a magnetic field between said cathode and said resonators, the field having lines of force perpendicular to the length thereof and an intensity adapted to deflect electrons emitted along the length of said surface in arcuate paths having a portion substantially parallel to said aligned walls, and concentrated across said openings in succession and terminating in said cathode whereby the electrons are velocity modulated in the field of the first resonator and transmit energy to the field of the second resonator, and means coupled to said second resonator for extracting high frequency oscillations.

9. An electron discharge device with means for producing a concentrated electron beam comprising a first and second cavity resonator, one wall of each said resonator being provided with an opening through which the oscillating field of the resonator can extend, a first and a second cathode mounted adjacent said wall of the first and second resonators respectively and having electron emitting surfaces of substantial length in one direction, means connected between said resonators and said cathode for producing a potential difference therebetween, and means adjacent the space between said resonator and cathodes for producing a magnetic field therebetween, the field having lines of force parallel to said emitting surfaces and perpendicular to said direction of the length thereof and an intensity adapted to deflect electrons emitted along the length of the emitting surface of said first cathode in arcuate paths each having a substantial portion equidistant from the wall of said first resonator, concentrated across the opening therein, and terminating in the emitting surface of said second cathode, said resonator walls being adjacent each other whereby the electrons in said paths are velocity modulated by the first resonator field and electrons are secondarily emitted from said second cathode past said second resonator opening.

10. An electron discharge device according to claim 9 in which the resonator walls are flat and in a common plane substantially, and said emitting surfaces are flat and parallel to said common plane, the magnetic field intensity being adapted to deflect the electrons secondarily emitted along the length of said second cathode in arcuate paths having a substantial portion equidistant from the wall of the second resonator and concentrated across the opening therein,

whereby the secondarily emitted electrons give up energy to the second resonator field.

11. An electron discharge device with means for producing a concentrated electron beam comprising a cylindrical cathode having an electron emitting surface on the interior thereof, a tubular anode mounted concentrically inside said cathode, said anode having a cavity resonator therein and being provided with openings communicating with said resonator, means connected between said cathode and anode for producing a potential difference therebetween, and means adjacent the space between the cathode and anode for maintaining a magnetic field therein, the field having lines of force parallel to the axis of said cylindrical cathode and an intensity adapted to deflect electrons emitted from said cathode surface in arcuate paths having a substantial portion tangential to the anode surface and concentrated across the openings to said resonator.

12. A device according to claim 11 in which the anode comprises a plurality of strips parallel to the axis of the cathode surface and having narrow spaces between the strips forming said openings.

13. An electron discharge device having an envelope enclosing an anode structure having a generally planar surface and provided with a series of mutually spaced slots in said surface dividing the structure into separate anode elements, each of said slots forming a resonant system interconnecting two adjacent anode elements, a cathode structure including a generally planar member mounted in opposed substantially parallel relation to said planar surface of said anode structure and means for providing electrons in proximity to the said anode elements, means for maintaining said anode structure at a positive unidirectional electric potential with respect to said member for maintaining therebetween a unidirectional electric field substantially normal to said planar surface and said member, and means for producing a magnetic field parallel to said slots in the space between said anode and cathode structures whereby said anode structure may be set into high frequency resonance as a consequence of the resultant motion of electrons traversing said space.
